UNITED STATES PATENT OFFICE.

EUGENIA ROSS, OF NEW YORK, N. Y.

HAND-PROTECTING ATTACHMENT FOR UMBRELLAS AND CANES.

SPECIFICATION forming part of Letters Patent No. 295,586, dated March 25, 1884.

Application filed June 9, 1883. (No model.)

To all whom it may concern:

Be it known that I, EUGENIA ROSS, of New York city, in the county of New York and State of New York, have invented certain Improvements in Hand-Protecting Attachments for Umbrellas and Canes, of which the following is a specification.

This invention has for its object to provide an attachment for the handle of an umbrella or a cane adapted to cover the hand by which the umbrella or cane is held when in use so that the hand will be protected against cold and moisture.

The invention consists in a pocket or pouch, of any suitable material, adapted to be secured to an umbrella-stick or cane and form an open-bottomed bag or pocket entirely surrounding the handle and adapted to cover the hand in which the latter is held, as I will now proceed 20 to describe.

The accompanying drawing, forming a part of this specification, represents a perspective view of an attachment embodying my invention applied to an umbrella-stick.

25 In the drawing, a represents the stick or rod of an umbrella, and b represents my improved attachment, which is a bag or pouch of any suitable material—preferably water-proof—such as gossamer rubber cloth. I provide one 30 end of said bag with a device for securing it to the stick a. In the present instance said device is shown as a strip or band, e, of metal, having ears f f, which are clamped together by a screw, g, thereby confining the band in 35 the form of a ring in contact with the stick a. The construction of this device may be variously modified, however, without departing from the spirit of my invention. It may be a band of elastic fabric or rubber, with a suitable clasp for uniting its ends; or it may be an 40 endless ring of rubber, adapted to hold itself on the stick by its own elasticity. The bag is attached to the securing device in any desired manner, preferably by stitches passed through 45 holes provided in the band, if the latter be of metal, and when in use depends from the securing device around the handle, as shown. The lower end of the bag is open, to permit the insertion of the hand, and may have an 50 elastic gathering-cord, i, near its edge, to confine it closely around the wrist.

When the attachment is not in use, it may be reversed or turned upwardly on the stick a, so that it will not cover the handle, and will be covered by the ribs and cover of the umbrella, the cord i holding the bag in this position by the contraction against the stick of the umbrella.

When the umbrella is raised, the bag may be drawn down over the hand, as shown, thus effectually protecting the hand against cold or moisture.

I do not limit myself to the form of the attachment represented in the drawings, nor to any particular material. If desired, seal-skin 65 or other fur-skin may be employed as a material, in which case it may be found desirable to make the bag larger at the center than at the ends and provide it with a lining having an elastic gathering-cord like that of an ordinary muff.

The bag or pouch may, if desired, be lined with flannel or other fleecy material.

I am aware that a rubber cup has been detachably secured to the tip of an umbrella-stick for the purpose of catching the drip, and I do not claim such a device, my invention being confined to a bag or muff adapted to be secured to the handle of an umbrella or cane, and to receive and cover the hand that holds the same.

I claim—

1. The combination, with an umbrella-stick or cane, of a hand-protecting attachment composed of a bag or pouch secured to the handle portion of the stick or cane, and adapted to receive and cover the hand that holds the stick, as set forth.

2. The combination, with an umbrella-stick or cane, of a bag or pouch secured near the end of the stick by a clamping device, substantially as described, which confines one end of the pouch to the stick, the end of the pouch not so secured having a gathering device whereby it may be drawn about the wrist and serve as a protection for the hand, as set forth.

In testimony whereof I have signed my name to this specification, in the presence of two subscribing witnesses, this 4th day of June, 1883.

EUGENIA ROSS.
